UNITED STATES PATENT OFFICE.

WILLIAM H. EMERICK, OF CHICAGO, ILLINOIS.

DOOR.

1,405,507.

Specification of Letters Patent. Patented Feb. 7, 1922.

Application filed January 23, 1920. Serial No. 353,460.

To all whom it may concern:

Be it known that I, WILLIAM H. EMERICK, a citizen of the United States, residing at Chicago, in the county of Cook and State of Illinois, have invented certain new and useful Improvements in Doors, of which the following is a specification.

This invention relates primarily to certain novel improvements in doors whereby 10 a single door may be readily converted into a screen door for use in summer or into a storm door for use in the winter, and having the openings therein protected at all times by coarse wire screens.

15 The invention also has for its object the provision of a strong and substantial door of rigid construction which will maintain its shape and which can be readily fitted or adjusted from time to time as occasion may 20 require.

In the accompanying drawings illustrating a selected embodiment of the invention—

Fig. 1 is an elevation showing the outer side of the door.

25 Fig. 2 is a similar view with the facing plates removed.

Fig. 3 is a sectional view on the line 3—3 of Fig. 2.

30 Fig. 4 is a sectional view on the line 4—4 of Fig. 1.

Fig. 5 is an elevation of the inner side of the door showing a fine mesh screen in the upper opening and a solid closure for the lower opening.

35 Fig. 6 is a detail perspective view of a glass closure which may be arranged in the upper opening of the door.

Fig. 7 is a sectional view on the line 7—7 of Fig. 5, but showing the glass closure of 40 Fig. 6 in place of the fine mesh screen closure of Fig. 5.

Fig. 8 is a detail perspective view showing the coarse screen arranged between its securing plates.

45 Figs. 9 and 10 are detail sectional views similar to Fig. 7 showing different ways of mounting the plates on the door frame.

50 Referring to the drawings, the door comprises a frame of usual rectangular construction having the two side members 11, 11', the top member 12, the bottom member 13 and the intermediate member 14, all of said members being secured together in any approved manner and providing an upper opening 15 and a lower opening 16. Each

of said openings is permanently covered by a coarse mesh screen 17 of heavy wire, the edges of which are secured between two plates which are fastened by screws 18 to the door members. In Figs. 4 and 7 the lower 60 plate 19 is bent between its side edges to provide an offset inner edge which in conjunction with the flat outer plate 20 provides a recess to receive the edge of the coarse screen 17. In both of these figures 65 the frame members are rabbeted to receive the two plates 19 and 20 so that the outer face of the upper plates will lie flush with the outer face of the members. Facing plates 21 are secured on the outer sides of 70 the door frame members said plates corresponding substantially in width with said members. I prefer to provide the facing plates with slots 22 to receive screws 23 which pass through the slots and secure the 75 plates adjustably to the door frame members. The side facing plates project beyond the side edges of the door to overlap the adjacent edges of the door casing and form a tight, weather-proof joint. The slots 22 80 and screws 23 permit the side plates to be adjusted whenever necessary.

In Fig. 9 the plates 19 and 20 which constitute the frame for each coarse screen are only partly seated in the door frame member 85 and the facing plate 21 is offset at 21' to overlap said frame member as shown. In Fig. 10 the coarse screen frame is mounted on the outer face of the frame member, the outer plate 24 is offset between its ends to 90 provide a recess between its inner portion and the flat inner plate 25 to receive the wire mesh and the facing plate 26 is offset at 27 to lap over the rear edge of the wire mesh frame and lie flush with the offset 95 portion 24 of the outer plate of said frame.

The openings 15 and 16 are always protected by the coarse wire mesh screens 17, 17 which are securely held in place on the door frame by the screws 18 and the facing plates. 100 To use the door as a screen door I provide a screen 28 in a suitable frame 29 which is removably secured in each opening of the door. To use the door as a storm door I provide a glass 30 in a suitable frame 31 105 which is removably secured in the upper opening 15 of the door and a metal plate 32 in a suitable frame 33 which is removably secured in the lower opening 16 of the door. I prefer that the inner plate 19 or 25 of the 110

coarse screen frames should project inwardly into the openings 15, 16 of the door frame as beyond the edges of the frame members as shown in the drawings, to provide tight 5 joints for the removable fine screen or storm door frames 29, 31 and 33.

These inner plates should project inwardly a sufficient distance to overlap the removable 10 frames and exclude dirt and insects in the case of the fine screen frames, and the weather as well in the case of the storm door frames, and close any openings that might result from imperfect fitting or shrinking 15 of the removable frames in said openings.

Any suitable means may be employed for securing the removable frames in the door openings. In the drawings I have illustrated a simple means comprising a pair of 20 plates 34 mounted on the side members of the door frame for each door opening. Each of these plates is provided with a pair of angle slots 35 to receive the screws 36 by which the plates are mounted on the door 25 frame. The horizontal parts of the angle slots are arranged substantially parallel with the top and bottom of the door opening, and the vertical parts of the angle slots are arranged substantially parallel with the 30 sides of the door opening. The plates hang from the upper ends of the vertical parts of the slots in locking position and overlap the frames 29, 33 or 31, as the case may be. To release the frame in the door opening the 35 plates are lifted and moved outwardly, the horizontal parts of the slots engaging screws 36 and sustaining the plates in their opened adjusted position. This is a very simple fastening device, it can be operated easily, 40 and it will securely lock in place any of the frames provided for the door openings.

It will be understood from the foregoing description and drawings that I contemplate embodying my invention in one form in a 45 strong and substantial door which can be permanently mounted in its casing for use alternately and as occasion may require as a storm door and as a screen door. For this reason I have shown a substantial construction which is capable of being adjusted from 50 time to time and which is intended to be a permanent fixture. It may be hung in the door casing by hinges such as set forth in my companion application filed concurrently 55 herewith or by any other suitable hinges. The openings in the door are always protected by the coarse screens permanently mounted therein, and the change of the frames in the door openings can be easily 60 and quickly effected. I may provide a glass frame for the lower opening as well as for the upper opening, and a metal plate or other closed frame for the upper opening as well as for the lower opening. I may provide the door with but a single opening, such

as the upper opening, or I may provide more than two openings suitably disposed in the door frame.

The side face plates preferably extend from top to bottom of the door. The top 70 face plate 21' may extend from side edge to side edge of the door with its ends located beneath the upper ends of the side face plates or it may terminate at its ends at the inner edges of the side face plates. The 75 middle face plate 21" and the bottom face plate 21''' may be made like the top face plate, but I prefer that their ends should terminate at the inner edges of the side face plates. The top and bottom face plates are 80 preferably provided with slots to receive the screws by which they are fastened to the door frame to permit these plates to be adjusted up or down as may be required. This is particularly important for the bottom face 85 plate because if the door sags at all, it will drag on the threshold, and hence it is convenient and desirable to provide means for adjusting the bottom of the door as may be required. It is not necessary to adjust the 90 middle face plate 21" up or down, although the screw holes may be slots to permit such adjustment if desired. The coarse screen frames may be made of strips extending 95 along the side edges of the door openings and cross strips at the top and bottom edges of the door openings, and secured together upon the interposed edges of the screens 17 and to the door frame. The top plate 20' has depending legs 20" which abut against 100 the legs 38 of a base plate 39 which is secured to the door frame at its lower edge. The two plates 20' and 39 form, in effect, a complete skeleton plate frame for the bottom member 13 of the door, and they are made 105 in this skeleton form so that if occasion requires that they be cut down to adjust the door to its casing, the work can be done very quickly by simply trimming the abutting edges of the legs.

110 I may provide the rear edge of the door with one or more dowel pins 40 to enter dowel openings 41 in the door casing 42. If ordinary hinges are used to swing the door, these dowel pins will prevent the door from 115 being removed, when closed, by withdrawing the hinge pintles.

I claim:

1. A door having an opening therein, a screen on the outer side of the door over said opening, plates embracing the edges of said screen and secured to the door, the inner plates projecting within said opening, a removable frame arranged within said opening back of said screen and abutting against 125 said inner plates, and means for holding said frames in place.

2. A door having an opening therein, a coarse screen closing said opening, plates fastened to the door at the edges of said open- 130

ing and embracing the edges of said screen, and facing plates fastened on the door over said screen plates.

3. A door having an opening therein, a coarse screen closing said opening, plates arranged one over the other and secured to the door at the edges of said opening, one of said plates being offset relative to the other plate to form a recess for the reception of 10 the edge of the coarse screen, and facing plates secured to the door over said screen plates.

4. A door having two openings therein one above the other, a coarse screen secured 15 in said openings, a plate at each of the edges of said openings and offset at its inner edge to form a recess to receive the edge of the coarse screen, facing plates extending from top to bottom of the door at the side edges 20 of said openings and secured to the door over the offset plates at the side edges of the coarse screens, and plates secured to the door over the offset plates at the edges of the screen at the top and bottom of each of 25 said openings.

5. A door having an opening adjacent the

bottom thereof, a screen secured to the door to close said opening, a plate secured to the door and overlapping the lower edge of the screen, and a second plate secured to the door 30 adjacent its lower edge, said plates having oppositely disposed legs at their ends.

6. A door having openings therein one above the other, screens for said openings, frames embracing the edges of said screens 35 and secured to the door at the edges of said openings, and facing plates adjustably mounted on the door independent of the screen frames and covering said screen frames.

7. A door having a pair of openings therein one above the other, screens for said openings, frames embracing the edges of said screens and secured to the door at the edges of said openings, facing plates on the door and 45 covering the screen frames, the side facing plates extending from top to bottom of the door and the transverse facing plates being located between said side facing plates, and means for securing the facing plates to the 50 door independent of said screen frames.

WILLIAM H. EMERICK.
